UNITED STATES PATENT OFFICE.

WILLIAM ANTON SCHULER, OF NEW YORK, N. Y.

DESIGN FOR A CHAIN-CLASP.

57,385.

Specification for Design. Patented Mar. 15, 1921.

Application filed November 17, 1919. Serial No. 338,779. Term of patent 14 years.

To all whom it may concern:

Be it known that I, WILLIAM ANTON SCHULER, a citizen of the United States, and residing at New York, in the county of New York and State of New York, have invented a new, original, and ornamental Design for a Chain-Clasp, of which the following is a specification, reference being had to the accompanying drawing, forming part thereof.

The figure is a perspective view of a fastener, showing my new design.

I claim:

The ornamental design for a chain clasp, as shown.

WILLIAM ANTON SCHULER.
